CONVERSION OF HYDROCARBONS

Kenneth M. Watson, Chicago, Ill., assignor to
 Universal Oil Products Company, Chicago, Ill.,
 a corporation of Delaware

Application June 7, 1940, Serial No. 339,281

7 Claims. (Cl. 196—52)

This invention relates to a process for converting hydrocarbon oil into valuable products including high antiknock gasoline. More particularly it relates to a combination of catalytic and non-catalytic cracking steps employing a powdered cracking catalyst for converting a distillate fraction of hydrocarbon oil while cracking higher boiling oil and residual oil from both cracking steps in the non-catalytic cracking operation.

The charging stocks employed may be from any suitable source including petroleum or such stocks as shale oil, coal tar oil, etc. Two grades of gasoline are normally produced, one being a non-catalytic cracked gasoline of antiknock value suitable for use for ordinary motor fuel purposes and the other being a premium grade gasoline of high antiknock value.

In one specific embodiment the present invention comprises treating a distillate fraction of hydrocarbon oil with a powdered catalytic composite under catalytic cracking conditions of temperature and pressure, separating a portion of liquid reaction products containing catalyst in suspension, recycling a portion thereof, recovering a further portion substantially free of catalyst, passing it to a non-catalytic cracking step hereinafter described, recovering the gasoline and gas from the catalytic cracking step, recycling a portion of the insufficiently converted oil; separately treating a higher boiling hydrocarbon oil together with the portion of liquid reaction products previously mentioned, in a non-catalytic cracking step under conditions of temperature and pressure adequate to produce substantial yields of gasoline, recycling a higher boiling portion of insufficiently converted oil to the non-catalytic cracking step, supplying an intermediate boiling fraction of insufficiently converted oil to the aforesaid catalytic cracking step, and recovering the gasoline from said non-catalytic cracking step.

The invention is further understood by reference to the accompanying drawing which is diagrammatic and should not be interpreted as limiting the invention to the exact apparatus shown.

A distillate fraction of hydrocarbon oil such as gas oil, kerosene distillate or wax distillate, is introduced through line 1, valve 2, pump 3 and valve 4 to coil 5 which is disposed in heater 6. 50 A powdered catalytic agent is introduced from catalyst charger 7 through line 8 containing valve 9, pump 10 and valve 11. The catalyst may be suspended in a portion of the charging stock, may be introduced in dry form, or may be sus-

pended in a fraction of reaction products or other suitable carrying medium.

The catalyst may comprise any suitable cracking catalyst such as, for example, silica-alumina, silica-zirconia or silica-alumina-zirconia composites which may or may not have deposited thereon, promoting oxides such as those of chromium, molybdenum, tungsten, vanadium, titanium, thorium, etc. These composites are made in part by the separate or simultaneous precipitation of the components followed by washing and drying steps to substantially eliminate alkali metal ions from the composite. Another type of catalyst which may be useful comprises relatively inert carriers such as alumina, magnesia, titania, zinc oxide and the like having deposited thereon relatively minor portions of promoting oxides of chromium, molybdenum, tungsten, vanadium, etc. Still another type of catalyst which may be employed to advantage is the naturally-occurring earth type which may be further activated by treatment with chemicals including mineral acids. It should be borne in mind that the catalysts mentioned are not necessarily equivalent in their action.

The mixture of oil and catalyst is heated in coil 5 to a temperature within the range of approximately 500—1200° F. and preferably within the range of 650—1000° F. under pressure adequate to maintain a substantial portion of the oil boiling above the gasoline range, in liquid phase. The heated mixture passes through line 12 containing valve 13 to catalytic reactor 14 which may comprise a reaction chamber in which a liquid level is maintained. The charge from line 12 is introduced to the catalytic reactor at a point below the surface of the liquid contained in said reactor in order to obtain additional conversion and likewise to keep the mixture agitated and prevent undue separation of the catalyst. The vaporous portion of reaction products including the gasoline and gas formed is removed through line 15 containing valve 16 to fractionator 17. Gasoline and gas are recovered through line 18, valve 19, condenser 20 and valve 21, being collected in receiver 22. Gaseous reactants may be removed through line 23 and valve 24 to suitable absorption equipment not shown. These gases may be further treated by alkylation and/or polymerization steps to produce additional quantities of high antiknock gasoline. The gasoline may be withdrawn through line 25 and valve 26 to suitable stabilizers not shown and may be given such additional treatment as may be necessary to produce a finished product. The

gasoline produced at this point is normally of high antiknock value of the order of 75-80 octane number or higher and may be used as such or may be used in blends with gasoline of low anti-knock properties to increase the octane number thereof. The portion of reactants boiling above the gasoline range is withdrawn from fractionator 17 through line 27 and valve 28 to line 29 containing pump 30 and valve 31, and being returned thus to the catalytic cracking step by way of line 1. A liquid portion of reaction products from reactor 14 is removed through line 32 and valve 33 to settler 34. Here sufficient time is allowed to permit substantial settling of the catalytic agent so that the catalyst concentrates in the lower portion of the settler. Oil containing a large quantity of catalytic agent is withdrawn through line 35 containing valve 36, pump 37 and valve 38. The catalyst may be recovered therefrom and be regenerated by suitable treatment with an oxygen-containing gas whereby the hydrocarbonaceous material is burned off. A portion of the catalyst-oil concentrate may be passed through line 39 and valve 40 to catalytic reactor 14 in order to build up a high concentration of catalyst in the reactor. By means of this expedient it is possible to maintain a relatively high concentration of catalyst in the reaction zone without necessity for adding such large quantities to the charging stock initially. Thus while from approximately 0.1-20% and preferably 0.1-5% of catalyst may be added with the charging stock, much greater concentrations of catalyst can be maintained in the reaction zone. The comparatively clear oil from the top of settler 34 is decanted through line 41, valve 42, pump 43 and valve 44 joining with line 45. The oil is mixed with incoming hydrocarbon oil which may be any heavy hydrocarbon oil such as topped crude oil, reduced crude oil and the like, which is introduced through line 45, valve 46, pump 47 and valve 48, passing to coil 49 which is disposed in heater 50. Here the mixture is treated under non-catalytic cracking conditions of temperature and pressure and passed through line 51 containing valve 52 to reaction chamber 53. The temperatures maintained are of the order of 850-1100° F. under pressures of approximately 100-1000 pounds per square inch. The reaction products are passed through line 54 controlled by valve 55, entering vaporizing chamber 56 at a reduced pressure within the range of approximately 25-200 pounds per square inch. A liquid portion of reactants unsuitable for further conversion is withdrawn through line 57 containing valve 58 and may be used as a fuel. The vaporous products from chamber 56 are passed through line 59 and valve 60 to fractionator 61. Gasoline and gas are recovered through line 62, valve 63, condenser 64, valve 65 and receiver 66. Gases are withdrawn through line 67 and valve 68 and may be treated as previously indicated for the catalytically produced gases. Gasoline is withdrawn through line 69 and valve 70 to be given such subsequent treatment as may be necessary to produce a finished motor fuel. The octane number of gasoline produced in this manner normally ranges from approximately 65-75 and is suitable with or without the addition of tetraethyl lead for use as a motor fuel. High boiling reflux from fractionator 61 is returned for further cracking by way of line 71 containing valve 72, pump 73 and valve 74, joining with line 45. An intermediate boiling side cut may be

passed through line 75 and valve 76 joining with line 29 and passing thence to line 1.

When treating a Mid-Continent topped crude oil in the manner described, a yield of 59% of gasoline may be produced, of which a portion is a catalytically cracked product having an octane number of approximately 79, a further portion of polymer gasoline of 83 octane number, the remainder being a non-catalytically cracked product with an octane number of 72. A silica-alumina catalyst may be used for the catalytic portion of this process at a temperature of approximately 1000° F. and a pressure of 50 pounds per square inch while using a temperature of 900° F. and a pressure of 250 pounds per square inch in the non-catalytic cracking step.

It should be borne in mind that the above example is given for illustrative purposes only and should not be interpreted as unduly limiting the invention to the exact conditions or catalysts employed.

I claim as my invention:

1. A process for the conversion of hydrocarbon oil which comprises catalytically cracking a relatively light oil in the presence of a powdered cracking catalyst and under a pressure sufficient to maintain a substantial portion thereof in liquid phase, separating vapors from catalyst containing liquid reaction products, returning one portion of said catalyst containing liquid reaction product to the catalytic cracking step, subjecting another portion of said liquid reaction products substantially free of catalyst to pyrolytic conversion together with a residual hydrocarbon oil, fractionating cracked vapors from the last mentioned conversion step to separate reflux condensate from the fractionated vapors, and supplying at least a portion of said reflux condensate to the catalytic cracking step.

2. The process of claim 1 wherein the cracking catalyst is selected from the group consisting of silica-alumina, silica-zirconia and silica-alumina-zirconia.

3. The process of claim 1 wherein the catalytic cracking step is carried out at a temperature within the range of approximately 500-1200° F. and a pressure of 50-1000 pounds per square inch.

4. The process of claim 1 wherein the non-catalytic cracking step is conducted at a temperature within the range of approximately 850-1100° F. and a pressure of approximately 100-1000 pounds per square inch.

5. A process for converting hydrocarbon oil into substantial yields of gasoline and gas which comprises mixing a distillate fraction of said hydrocarbon oil with a powdered catalytic agent, heating the mixture under catalytic cracking conditions of temperature and pressure, passing the heated mixture to a reaction zone maintained at catalytic cracking conditions of temperature and under pressure sufficient to maintain a substantial quantity of oil boiling above the gasoline range in liquid phase, maintaining a liquid level in said reaction zone, passing a vaporous fraction of reactants to a fractionating step, recovering gasoline and gas therefrom and recycling insufficiently converted oil for further conversion, withdrawing a portion of the liquid reactants containing catalyst in suspension from said reaction zone, subjecting the mixture to a settling step whereby the catalytic agent separates from one portion of the oil and concentrates in another portion, returning a portion of the catalyst-oil concentrate to said reaction zone thereby main-

taining a relatively high concentration of catalyst therein, and removing a further portion of said concentrate and recovering catalyst therefrom, supplying the portion of liquid reactants which is substantially free of powdered catalyst together with residual hydrocarbon oil to a non-catalytic cracking step, subjecting the reaction products therefrom to a fractionation step, recovering gasoline and gas, returning a portion of higher boiling insufficiently converted oil for further conversion in said non-catalytic cracking step and supplying a portion of intermediate boiling insufficiently converted oil to the above described catalytic cracking step.

6. A process for the conversion of hydrocarbon oil which comprises catalytically cracking a relatively light oil in the presence of a powdered cracking catalyst and under a pressure sufficient to maintain a substantial portion thereof in liquid phase, separating vapors from catalyst containing liquid reaction products, returning one portion of said catalyst containing liquid reaction products to the catalytic cracking step, subjecting another portion of said liquid reaction products substantially free of catalyst to pyrolytic conversion together with a residual hydrocarbon oil, fractionating cracked vapors from the

last mentioned conversion step to separate light and heavy reflux condensate from the fractionated vapors, supplying said light reflux condensate to the catalytic cracking step and the heavy reflux condensate to the pyrolytic cracking step.

7. A process for the conversion of hydrocarbon oil which comprises catalytically cracking a relatively light oil in the presence of a powdered cracking catalyst and under a pressure sufficient to maintain a substantial portion thereof in liquid phase, separating vapors from catalyst containing liquid reaction products, supplying said catalyst containing liquid reaction products to a separator and therein concentrating the catalyst in one portion of the liquid reaction products, returning at least a portion of the liquid reaction products containing the catalyst to the catalytic cracking step, subjecting the liquid reaction product substantially free of catalyst to pyrolytic conversion together with a residual hydrocarbon oil, fractionating cracked vapors from the last mentioned conversion step to separate reflux condensate from the fractionated vapors and supplying at least a portion of said reflux condensate to the catalytic cracking step.
